CLAMP FOR DENTURE FLASKS

Felix C. Montuori, Washington, D. C.

Application December 31, 1945, Serial No. 638,593

14 Claims. (Cl. 18—33)

1
This invention relates to dental apparatus and more particularly to a novel clamp for denture flasks, for placing said flasks under uniform pressure throughout their top and bottom areas.

Heretofore, it has been the practice to hold the sections of a denture clamp closed, when immersing it in a hot medium, by means of a frame on the order of a screw press. That is to say, according to current practice the denture flask is placed in a frame whose upper transverse portion carries a clamping screw which is forced toward the sections of the flask by manipulating a suitable wrench. The screw is provided with an annular foot portion so that frequently when the screw is adjusted to hold the sections of the flask together, the unmeasured or uncontrolled pressure of the screw flexes the adjacent wall of the upper flask section inwardly, and the resulting distortion of the flask wall in turn results in distortion of the filling of the flask and in turn damages the denture. As can well be appreciated, since absolute accuracy is desirable in order to prevent damage to the plate being formed, the distortion resulting from present practice often requires the denture to be re-made, thus not only losing time and incurring additional expense, but generally adding to the tediousness of the operation.

Accordingly, the present invention has primarily in view a novel clamp for equally distributing holding pressure to the assembled mating sections of a denture flask in such a way that the pressure on the top and bottom sections of the flask is uniformly distributed over the entire top and bottom walls of the flask, while, at the same time the sections themselves are held in tightly closed relation during the curing operation. In that connection the invention contemplates a simple and practical form of clamp including opposite jaw members which are normally urged together by constant uniform spring energy and which jaws may be separated to receive the flask by applying external pressure to a portion of the device which enables the flask to be inserted so that when extraneous pressure is released, the jaws of the clamp will hold the flask together by uniform well-distributed pressure incident to the novel spring arrangement employed.

A further object of the invention is to provide a device of the type set forth, wherein the essential features are susceptible of modification into several forms of embodiment, all of which are practical and reliable and which may be used in conjunction with a hydraulic press, or other appropriate means.

2
With the above and other objects in view which will more readily appear as the nature of the invention is better understood, the same consists in the novel construction, and combination of parts, hereinafter more fully described, illustrated and claimed.

A preferred and practical embodiment of the invention is shown in the accompanying drawings, in which:

10. Figure 1 is a front elevation of the improved clamp.
11. Figure 2 is a top plan view.
12. Figure 3 is an end elevation.
13. Figure 4 is a vertical sectional view taken on the line 4—4 of Fig. 2, and diagrammatically indicating a source of extraneous pressure for opening up the jaws of the clamp against the force of the springs.
14. Figure 5 is a detail vertical sectional view taken on the line 5—5 of Fig. 1.
15. Figure 6 is a side elevation of a modified form of the invention, the same being partly in section.
16. Figure 7 is a vertical sectional view taken on the line 7—7 of Fig. 6.
17. Figure 8 is a front elevation of another form of the invention, a portion thereof being in section.
18. Figure 9 is a vertical sectional view taken on the line 9—9 of Fig. 8.
19. Figure 10 is a front elevation and Fig. 12 is a side elevation of a further modification.
20. Figure 11 is a cross section taken on the line 11—11 of Fig. 10.
21. Similar reference characters designate corresponding parts throughout the several figures of the drawings.
22. According to the embodiment of the invention shown in Figs. 1 to 5 inclusive, it will be observed that the present clamp essentially includes the upper and lower jaw members A and B which are intended to clamp therebetween a conventional denture flask designated generally as F, by dotted lines in Figs. 1 and 4.
23. The jaw members A and B are slidably inter-fitted and are drawn toward each other by the constantly energized springs S. The arrangement is such that the jaws A and B are normally held together by the springs S in such a way that they are initially spaced closer together than the normal thickness of the flask F so that when pressure is applied to elements associated with one of the jaw members they may be separated to admit the flask, and, after the extraneous pressure is removed the flask will be uniformly clamped by spring pressure between the jaws.
24. A and B.

Referring first to the upper jaw member A, it will be observed that the same is provided inwardly of its ends with the substantially right angularly disposed guide arms or members 1 which extend downwardly beyond the jaw B, as shown, to provide the supporting feet 2 intended to rest on a suitable fixed base C, which, as will presently appear, may be the anvil of a hydraulic press, or any other appropriate surface. The lower jaw member B is provided with the substantially right angularly disposed upwardly directed guide arms 3 which are in sliding contact with the inner faces of the guide arms 1 of the jaw member A. As shown in the drawings, it will be observed that the upper plunger ends 4 of the arms 3 project through the slots 5 of the jaw member A. The guide arms 3 are provided inwardly of their upper ends 4 with the shoulders 6 which abut against the inner face of the upper jaw member A. Thus, the distance between the shoulders 6 and the upper face of the lower jaw B defines the space for receiving the denture flask, but when the clamp is not in use the said space or distance just referred to is less than the depth or thickness of the flask. On the other hand, when a flask is inserted between the jaws, this distance is increased, and the jaws subject the flask sections to pressure.

The jaw members A and B are respectively provided with the outwardly projecting ears 7 and 8 to which the opposite ends of the springs S are anchored, thereby tending to draw the jaws A and B together and, when the jaws are empty, maintaining the abutment shoulders 6 in the position shown in Fig. 5. In connection with the guide arms 2 of the jaw member A it will be observed that they are guided between the lower ears 8-8 of the jaw member B so that in effect the jaw member B is slotted to receive the guide arms 1, substantially after the same fashion as the slots 5 receive the upper ends 4 of the guide arms 3 of the jaw members B.

When the device is assembled as shown in Figs. 1 to 5 inclusive, and it is desired to insert the dental flask F, the upper ends 4 of the guide arms 3 are subjected to extraneous pressure by any appropriate means, such for example, as the head H of a hydraulic press, while the extension feet 2 of the arms 1 rest on the anvil C of the press. As shown in Fig. 4 the jaws A and B are separated sufficiently to permit of the insertion or removal of the flask F. Fig. 1 of the drawings illustrates the flask clamped between the jaws and ready to be immersed in boiling water or the like, for the conventional curing operation.

From the foregoing it will be understood that the springs S are under constant tension even when the clamp is not in use, the springs S normally holding the jaws A and B in the relationship shown in Fig. 5. However, when it is desired to open the same to admit a flask between the jaws, they are separated as shown in Fig. 4, and, when pressure is removed the sections of the flasks are uniformly clamped together, accurately, and without distortion.

A modification of the invention is illustrated in Fig. 6 wherein the base C' is provided with upstanding tubular columns or equivalent members 10. The jaw A' is rigidly carried by the upper end of the tubular member 10 as indicated at 11, while the lower jaw B' is slidably mounted on the tubular columns 10-10. As shown in Figs. 6 and 7 the said members 10 are provided with slots 12 which receive the cross pin 13 of a plunger 14 whose upper end projects beyond the

upper jaw member A'. The jaw member A' and B' are urged toward each other by the tension springs S'. Thus, when the clamp is not in use the lower jaw B' is limited in its upward movement, under the force of the springs S', by the cross pins 13 engaging the upper ends of the slots 12. When it is desired to admit a flask for clamping engagement between the jaws A' and B' it is only necessary to apply extraneous pressure to the upper ends of the plungers 14. In that event the cross pins 13 will force the lower jaw member B' downwardly a sufficient distance to permit separation of the jaw members A' and B' to admit a flask.

In Figs. 1 to 6 inclusive, the springs S and S' are constantly in tension. However, Figs. 8 and 9 of the drawings illustrate a modification of the invention where the springs S² are of the compression type. As will be observed from these figures, the jaw member A² is provided with the right angularly disposed guide arms 15 which terminate in the inwardly disposed feet 16 intended to rest on an anvil or equivalent base C². The guide arms 15 are medially slotted as indicated at 17, thereby to receive the studs 18 carried by the upwardly extending guide arms 19 of the lower jaw member B. The guide arms 19 are provided with shoulder portions 20 which abut against the under face of the upper jaw A², as shown in Fig. 9. The guide arms 19 have upper plunger portions 21 which are of less width than the arms, thereby to form the shoulders 20 previously referred to and also enable the arms 19 to be guided in the slots 22 formed in the upper jaw member A². The compression springs S² are placed between the upper surfaces of the supporting feet 16 and the underside of the lower jaw member B², thereby normally tending to force the lower jaw member B² upwardly as far as the shoulders 20 on the arms 19 will permit because of their engagement with the underside of the upper jaw A². The springs S² may be centered and held in their assembled position by appropriate studs 23-23 on the jaw B² and the studs 24-24 on the inner turned supporting feet 16.

When it is desired to place a flask between the jaw members A² and B² it is only necessary to apply pressure on the extensions 21 of the arms 19, thereby further compressing the springs S² and spacing the jaws sufficiently apart to admit the flask. After the flask has been inserted, the extraneous pressure may be removed and the flask will be firmly secured in the clamp so that it can be subjected to the usual curing operation.

In the form shown in Figs. 10-12 the upper jaw member A³ has the downwardly extending side arms 15³ provided with shoulders 15⁴ medially thereof, while their lower ends are formed as at 16³ into the base C³. The lower jaw B³ is recessed at its ends, as indicated at 25 to provide slots for receiving the arms 15³ and also provide the plunger ears 27. The springs S³ are compressed between the base C³ and lower jaw B³, the said springs being centered on studs 23³ and 24³, respectively on the jaw B³ and base C³. When extraneous pressure is applied to ears 27, the jaws are separated to admit a flask.

In all forms of the invention, the essential characteristics are a pair of jaw members urged together under spring force but limited as to their movement toward each other in such a way that the normal space between the jaws is less than the depth of a dental flask. When it is desired to insert a dental flask, one of the jaws is moved relative to the other, against the force

of the springs, thereby separating the jaws to admit the flask, and when pressure is removed the flask is held between the jaws by the force of spring energy.

Without further description it is believed that the features and advantages of the invention will be readily apparent to those skilled in the art and it will of course be understood that changes in the form, proportion and minor details of construction may be resorted to, without departing from the scope of the appended claims.

I claim:

1. A clamp for uniformly distributing holding pressure to the assembled mating sections of a denture flask, comprising, a pair of opposite jaw members of width and length to receive a flask therebetween, means for limiting the movement of the jaws toward each other for a distance less than the thickness of an assembled flask, constantly energized spring means for moving said members together, and means on one of the jaw members adapted to receive an extraneous source of applied pressure to separate the jaw members against the force of said springs to admit an assembled flask, and, whereby upon the release of said extraneous pressure the said springs hold the inserted flask sections together.

2. A clamp for uniformly distributing holding pressure to the assembled mating sections of a denture flask, comprising, a pair of parallel jaw members interfitted for limited movement toward each other initially to provide a space therebetween of less thickness than an assembled flask, constantly energized springs tending to hold said jaws in said initial spaced relation, and means carried by one of the jaw sections for the application of external pressure to separate the sections against the force of the springs thereby to receive a flask, and, when the extraneous pressure is removed, the sections of the flask are clamped together.

3. A clamp for uniformly distributing holding pressure to the assembled mating sections of a denture flask, comprising, a pair of opposite parallel jaw members having slots, a pair of spaced guide arms carried by each jaw member and disposed substantially at right angles thereto, the arms of one member being in slidable contacting relation to the arms of the other jaw member, the arms of one section having shoulders for abutting the inner face of the opposite jaw member, and the arm of the other section extending beyond the lower face of said bottom jaw member to provide supporting feet, ears extending outwardly from the end of each jaw member substantially in the plane thereof, and constantly tensioned springs having their opposite ends secured to said ears, whereby said jaw members are drawn toward each other a distance less than the thickness of an assembled flask, as determined by the said shoulders, and, whereby, when the supporting feet are subjected to extraneous pressure, the jaw members are separated to receive an assembled flask, and when the extraneous pressure is removed the sections of the flask are clamped together.

4. A clamp for uniformly distributing holding pressure to the assembled mating sections of a denture flask, comprising, a pair of tubular members having slots, an upper jaw rigidly carried by the upper ends of said tubular members, a lower jaw slidably mounted on the lower portions of the tubular members, springs connecting the upper and lower jaw members, plungers in said tubular members, cross pins in said plungers

and slideable in said slots, said pins bearing against the upper sides of the lower jaw, whereby the upward movement of the lower jaw is limited, and, when the plungers are subjected to pressure, the lower jaw is moved away from the upper jaw.

5. A clamp for uniformly distributing holding pressure to the assembled mating sections of a denture flask, comprising, an upper jaw having downwardly extending arms provided with slots and inturned supporting feet, said upper jaw having slots adjacent the ends thereof, a lower jaw having upwardly extending arms slidably engaging the arms of the upper jaw and the upper plunger ends of said arms entering the slots of the jaw, studs carried by the arms of the lower jaw and riding in the slots of the arms of the upper jaw, and compression springs mounted between the underside of the lower jaw and said inturned supporting feet.

20. 6. A clamp for uniformly distributing holding pressure to the assembled mating sections of a denture flask, comprising, an upper jaw having downwardly extending arms and inturned supporting feet to provide a base, said arms having shoulders, a lower jaw member formed at its ends to slidably receive the downwardly extending arms of the upper jaw member, plunger ears on the lower jaw member for receiving a source of extraneous pressure, and springs confined between the base and the lower jaw.

30. 7. A clamp for uniformly distributing holding pressure to the assembled sections of a denture flask, comprising, a pair of relatively movable upper and lower jaw members, base engaging means for fixedly supporting said upper jaw member, means for limiting the movement of said lower jaw member toward said upper jaw to a distance less than the thickness of an assembled flask, means carried by said lower jaw and extending above said upper jaw for moving said lower jaw away from said upper jaw, and spring means for urging said jaws toward each other to subject said flask to uniform predetermined pressure.

45. 8. A clamp for holding a denture flask, comprising a pair of opposed jaws operable to hold a denture flask therebetween, means for limiting movement of one jaw toward the other for a distance less than the depth of said denture flask, 50 means associated with one of said jaws adapted to receive an extraneous force capable of moving said one jaw relative to the other to expand the space between said jaws for the reception therebetween of a denture flask, and spring means associated with one of said jaws constantly tending to contract the space between said jaws whereby the denture flask received therebetween will be yieldingly held by said jaws, said spring means being operable to permit expansion of the space between said jaws when one of them receives the extraneous force aforesaid.

65. 9. A clamp for holding a denture flask, comprising a pair of opposed jaws operable to hold a denture flask therebetween, means for limiting movement of one jaw toward the other for a distance less than the depth of said denture flask, a projection on one of said jaws adapted to receive an extraneous force capable of moving said one jaw relative to the other to expand the space between said jaws for the reception therebetween of a denture flask, and spring means associated with one of said jaws constantly tending to contract the space between said jaws whereby the denture flask received therebetween will be yieldingly held between said jaws.

10. A clamp for holding a denture flask, comprising a pair of relatively movable jaws operable to hold a denture flask therebetween, means for limiting movement of the jaws toward each other for a distance less than the depth of said denture flask, means associated with one of said jaws adapted to receive an extraneous force capable of moving said jaws apart so they may receive a denture flask therebetween, and spring means constantly urging said jaws toward each other, said spring means being yieldable to permit separation of said jaws when one of them receives the extraneous force aforesaid and operable when said one jaw is relieved of said extraneous force to move said jaws toward each other so that said denture flask received therebetween will be yieldingly held thereby.

11. A clamp for holding a denture flask, comprising a pair of relatively movable jaws operable to hold a denture flask therebetween, means for limiting movement of the jaws toward each other, means associated with one of said jaws adapted to receive an extraneous force capable of moving said jaws apart so they may receive a denture flask therebetween, and means constantly urging said jaws toward each other, the last mentioned means being yieldable to permit separation of said jaws when one of them receives the extraneous force aforesaid and operable automatically when said one jaw is relieved of said extraneous force to move said jaws toward each other so that said denture flask received therebetween will be yieldingly held thereby.

12. A clamp for holding a denture flask, comprising a pair of relatively movable jaws operable to hold a denture flask therebetween, means for limiting movement of the jaws toward each other, means providing a projection on one of said jaws adapted to receive an extraneous force capable of moving said jaws apart so they may receive a denture flask therebetween, means providing a projection on the other of said jaws for engagement with a support beneath said one jaw, and means constantly urging said jaws toward each other, said last mentioned means being yieldable

5 to permit separation of said jaws when one of them receives the extraneous force aforesaid and operable automatically when said one jaw is relieved of said extraneous force to move said jaws toward each other so that said denture flask received therebetween will be yieldingly held thereby.

13. A clamp for holding a denture flask, comprising a pair of relatively movable jaws operable to hold a denture flask therebetween, means for limiting movement of the jaws toward each other, means providing a projection on one of said jaws adapted to receive an extraneous force capable of moving said jaws apart so they may receive a denture flask therebetween, said jaws having lateral projections, and spring means terminally connected to said lateral projections of the jaws and constantly urging said jaws toward each other.
14. A clamp for holding a denture flask, comprising a pair of opposed jaws operable to hold a denture flask therebetween, means for limiting movement of one jaw toward the other for a distance less than the depth of said denture flask, means each associated with one of said jaws and projecting beyond the other jaw and therefore adapted for application of a force capable of moving said one jaw relative to the other to expand the space between said jaws for the reception 30 therebetween of a denture flask, and spring means for urging the approach of said jaws.
